UNITED STATES PATENT OFFICE

HARRY J. FAERRINGTON, OF AUBURNDALE, MASSACHUSETTS

BOX FOR JEWELRY AND THE LIKE

Application filed March 29, 1928. Serial No. 265,682.

This invention relates to improvements in boxes or cases of an ornamental character which are usually covered with plush, leather, or other textile or fibrous material, and are designed for holding such articles as 5 jewelry, safety razors, and other devices intended for personal use, and comprises a specific modification of the invention more broadly disclosed in my co-pending application, Serial Number 265,681 filed March 29, 10 1928.

The principal object of the present invention is to provide a box comprising a base, a hollow side wall of inverted channel construction having an outer flange forming a continuous vertical face, a web forming the upper edge of the wall and presenting a rim simulating a thick wall, and means securing 15 said side wall to the base.

A further object of the invention is to provide a construction of the character above described in which the side wall may be formed from a sheet of metal, or from a suitably shaped and notched strip of structural 20 metal.

A further object of the invention is to provide a construction of this character in which the inner flange of the side wall is of less effective width than the outer flange forming 25 the continuous face of the side wall, with means for securing the base to the side wall engaging the narrow inner flange of the side wall and acting to clamp the outer flange thereof firmly against the base.

A further feature of the invention consists 30 in providing the inner flange of the side wall with an inwardly extending lip adapted to be engaged by suitable clamping means, such as a plurality of tabs on the base and clinched 35 over the inwardly projecting lip.

A further object of the invention is to provide a box of the character above described having an inverted channel-shaped side wall provided with covering material and, in 40 which the inner wall presents an abutment against which the filler or puff may be securely held by frictional engagement of the periphery thereof with the covering for such side wall.

These and other objects and features of the

invention will more fully appear from the following description and the accompanying drawings and will be particularly pointed out in the claims.

Preferred embodiments of the invention are 55 illustrated in the accompanying drawings, in which,

Fig. 1 is a perspective view of a box embodying the invention having a channel-shaped side wall formed integrally from a sheet of metal;

Fig. 2 is a perspective view showing the side wall partially formed and illustrating one step in the process of its construction;

Fig. 3 is a perspective view of a box comprising an integral side wall of inverted channel shape and illustrating one means for securing the inner flange of the side wall to the base;

Fig. 4 is a detail sectional view in perspective illustrating a different means for securing the side wall to the base;

Fig. 5 is a longitudinal sectional view of a box embodying the invention showing the base of the box provided with rim portions 75 extending angularly upwardly from the plane of the base, with its periphery projecting beyond the side wall and bent upwardly there-against, and also illustrating means engaging the inner flange of the side wall acting 80 to clamp the lower edge of the outer flange firmly upon the base;

Fig. 6 is a perspective view of a box having a continuous side wall of inverted channel shape formed from a strip of structural 85 shaped material and provided with a cover of like construction;

Fig. 7 is a perspective view of the body portion of the box illustrated in Fig. 3, illustrating the manner in which the strip forming the side wall is bent to produce the box;

Fig. 8 is a perspective view of the strip of structural shape used in producing the side wall of the box illustrated in Fig. 7; and,

Fig. 9 is a detail vertical sectional view 95 illustrating the construction of the assembled box and cover shown in Figs. 1, 5, and 6.

The box illustrated in Figs. 1, 2, and 3, comprises a base 1, and a side wall of channel construction comprising a web 2 which forms the 100

upper edge of the side wall and presents a continuous rim simulating a thick wall, a continuous outer vertical flange 3 forming the outer face of the wall, and an inner flange 4 which desirably extends downwardly in parallelism with the outer flange 3.

The base and side walls are formed separately by die cutting and die pressing machines. A suitable covering 5, of plush, leather, textile, or other fibrous material, may be applied to the side wall, and also if desired to the base before the base and side walls are assembled. The box may be made of any desired size, shape, or form. The base may 10 conform to the periphery of the side walls, but desirably may project beyond the periphery thereof and may be made to conform to or to depart from, the contour of the side wall as may be desired.

20 In the construction of the side wall a flat sheet is cut out to the desired contour and a central portion also cut out to present an edge 6 extending in substantial parallelism with the peripheral edge of the sheet. The slits 25 or notches 7 are cut to extend from the corners, or other portions of the cut-out area, to, or approximately to, the line which defines the inner margin of the upper edge or wall of the channel. The plate may then be bent by suitable dies, either first into the form illustrated 30 in Fig. 2 in which the outer flange 3 is bent downwardly from the web 2 and the inner flange thereafter bent down in a suitable manner, or the outer flange 3 and inner flange 4 35 may be bent down simultaneously to form a channel-shaped wall such as is illustrated in Fig. 3. By reason of the slits or notches the inner flange when bent downwardly will produce a series of sections instead of a continuous inner flange, but inasmuch as these all 40 form a part of the same flange construction such sections will be referred to as the flange. Desirably the lower margin of the flange may at the same time be bent inwardly at right 45 angles to the plane of the flange 4 to provide a lip 8; such lips being upon each of the sections will be referred to as a lip.

When the sheet has thus been cut and pressed it will assume the form of the side wall illustrated in Figs. 3, and 9. The web 2 and the inner flange 4 may be cut away before, during, or after the die-shaping process, so that the outer flange 3 will present a continuous wall along the back, but by reason of the omission of the web and inner flange will 50 provide a recess which will enable a suitable hinge to be secured directly to the rear wall. Desirably tabs 9 are punched inwardly from the flange within the recessed portion of the wall and are adapted to enter complementary slots in one of the plates 10 of a hinge member for securing the base to the top. This hinge member may be and desirably is of the 55 construction disclosed in my prior Patent No.

1,552,916, and need not be further described herein.

The base 1 desirably is provided with a plurality of tabs 11 partially cut out from and integral with the base and extending upwardly therefrom and bent over to engage the lip 8 projecting inwardly from the lower edge of the inner flange 4. The inner flange 4, having the inwardly turned lip, may be effectively shorter than the outer flange 3, so that when the tabs 11 upon the base engage such lips the lower edge of the outer flange will be pressed firmly against the base.

In the construction illustrated in Fig. 5, the base 1 is provided with an upwardly inclined rim portion 12 and the inner flange is illustrated as equal in width to the outer flange with the lip extending inwardly from the bottom thereof in substantially the same plane as the lower edge of the outer flange. 60 In this construction the upwardly sloping rim of the base 12 provides a sufficient separation between the lip and the base to enable the tabs 11 to clamp the lower edge of the outer flange firmly upon the base. In the construction illustrated in Fig. 5, a covering material extends from beneath the edge of the outer flange 3, over the outer face thereof, across the web 2 of the channel which forms the upper edge of the side wall, thence downwardly along the inner flange 4. The covering 65 13 of the base extends over the base, around the peripheral edge thereof which projects beyond the side wall, thence inwardly upon the upper face of the base, and beneath the lower edge of the outer flange 3, so that the covering material of the side wall and base are both interposed and clamped between the lower edge of the outer flange of the side wall and the base. The projecting edge of the base may be folded up against the outer face of the side wall, as illustrated in Fig. 5, or may be permitted to extend beyond the face of the wall, as illustrated in 70 Figs. 1 and 3, as may be desired.

In Fig. 4 a modified form of mechanism for clamping the side wall to the base is illustrated in which the inner flange 4 of the side wall is provided with recesses 14 in proximity to the lower edge thereof, which is not provided with a lip, and the ends of the tabs 11 bent into the recesses and downwardly upon the lower edge thereof.

In Figs. 6, 7, and 8, a modified construction is illustrated in which the side wall is formed of a structural-shaped strip of material, preferably of inverted channel form. A preferred form of strip, adapted to produce the side wall of a rectangular box such as is illustrated in Figs. 6 and 7, is shown 80 in Fig. 8, and comprises a channel having a web 15, an outer flange 16, an inner flange 17 extending downwardly in parallelism with the flange 16, and preferably provided at its lower end with a laterally extending 85

lip 18 which, when the strip is bent to form the wall of the box, projects inwardly. The web 15 and flange 17 with its lip 18 are notched in such a manner as to permit the outer flange 16 to be bent into the form of a rectangular box presenting flattened corners. In the construction illustrated in Fig. 8, the web is provided with two notches 19 and 20, separated by a truncated V-shaped projection 21, while the inner flange 17 and lip 18 are cut away in the planes of the outer edges of the notches 19 and 20. The notches in the flange and web are made such distances apart as to produce sides of the desired length. The notches may be spaced differently to produce boxes of differing contour. When the strip is folded the opposite edges of each notch abut and the V-shaped projections 21 fill the corners between the sides or sides and ends of the box to produce a hollow side wall having an effectively continuous upper edge, and also a substantially continuous inner flange and lip. The outer flange 16 desirably is continued beyond the end of the hollow wall to provide extensions 22 which, when the strip is bent into the desired form of side wall, abut at their ends in the same plane.

Desirably the abutting ends of the side wall are provided with interengaging means, such as a dovetail joint 23, adapted to hold the strip in place during the process of manufacture, and also to strengthen the strip. The vertical flange 22 desirably is provided with a plurality of tabs 24 partially cut from and integral with the strip and extending therefrom and engaging the plate 25 of a hinge, which may be of the character heretofore described. The side wall and the base may be covered with any suitable material and the covering material desirably may extend beneath the lower edge of the outer flange of the side wall, and also around the periphery of the base beneath the lower edge of the outer flange of the side wall as heretofore described.

Any suitable means may be provided for securing the base to the side wall. As illustrated herein the base 26 extends beyond the periphery of the side wall and is secured to the side wall by a plurality of tabs 27 which are partially cut from and integral with the base and extend upwardly therefrom over and into clamping engagement with the lip 17 of the side wall.

In this construction, as in the construction previously described, the inwardly extending lip 17 may lie upon the upper surface of the base of the box or may effectively terminate short of the base. This can be accomplished by forming the inner flange of less width, or by providing the base of the box with an upwardly inclined rim so that the bottom of the inner flange, or of the rib 17 thereof, will lie at a distance above the

base, thereby enabling the tabs 27, or other interengaging means, to force the lower edge of the outer flange of the hollow side wall firmly against the base. Any suitable cover may be secured to the complementary hinge plate 28. Desirably, however, the cover is of identical or similar construction to that heretofore described.

Boxes of this character desirably are provided with a collar extending around the inner edge of the rim of the side wall of the box. Such a device, as illustrated in Fig. 9, is applicable to any of the types of boxes herein described, and comprises a collar 29 having a covering 30 of satin, or other ornamental material. The lower edge of the collar 29 rests upon and desirably is secured to the lip 18 and the upper edge thereof projects a short distance above the plane of the upper edge of the side wall. The vertical inner flange of the hollow side wall provides a rigid support for the outer side of this collar.

A suitable filler, such as a pad or a puff 31, of a well known type may be sprung into the body of the box with its peripheral edge engaging the inner face of the collar, as illustrated in Fig. 9.

A suitable filler, such as a puff 32, may be similarly sprung into the cavity of the cover with the peripheral edge thereof engaging the inner flange 17 of the hollow side wall thereof, or the covering material therefor, which desirably extends along the inner face of said flange.

It will be understood that the embodiments of the invention particularly disclosed herein are of an illustrative character and are not restrictive, and that various changes in form, size, construction and arrangement of parts may be made within the spirit and scope of the following claims.

Having thus described the invention, what is claimed as new, and desired to be secured by Letters Patent, is:

1. A box comprising a base, a continuous hollow sheet metal side wall of inverted channel shape having an outer flange forming a continuous outer face of predetermined form, a web forming the upper edge of said wall and presenting a rim simulating a thick wall, an inner flange extending in substantial parallelism to said outer flange, and interlocking means on said base and wall securing said wall to said base.

2. A box comprising a base, a continuous hollow side wall of inverted channel shape having a flange forming a continuous outer face of predetermined form, a web forming the upper edge of said wall and presenting a rim simulating a thick wall, an inner flange extending in substantial parallelism to said outer flange, and means securing said inner flange to said base.

3. A box comprising a base, a hollow side

- wall of inverted channel shape having an outer flange forming a continuous vertical face, a web forming the upper edge of said wall and presenting a rim simulating a thick wall, an inner flange and interengaging means upon said base and said inner flange clamping said base to said side wall.
4. A box comprising a base, a hollow side wall of inverted channel shape having an outer flange forming a continuous vertical face of predetermined form, a web forming the upper edge of said wall presenting a rim simulating a thick wall, and an inner flange of less width than said outer flange, and means on said base engaging said inner flange and acting to clamp the outer flange firmly upon said base.
5. A box comprising a base, a hollow side wall of inverted channel shape having an outer flange forming a continuous vertical face of predetermined form, a web forming the upper edge of said wall presenting a rim simulating a thick wall, and an inner flange, a plurality of tabs cut out from and integral with said base extending therefrom and engaging said inner flange and acting to clamp the outer flange firmly upon said base.
6. A box comprising a base, a hollow side wall of inverted channel shape having an outer flange forming a continuous vertical face of predetermined form, a web forming the upper edge of said wall presenting a rim simulating a thick wall, and an inner flange having an inwardly projecting lip, means on said base engaging said lip and acting to clamp the outer flange firmly upon said base.
7. A box comprising a base, a hollow side wall of inverted channel shape having an outer flange member presenting a continuous vertical face of predetermined form, a web member forming the upper edge and an inner flange member extending in substantial parallelism with said outer flange member, certain of said members being notched to permit the construction of a side wall of a predetermined form and to provide a smooth continuous rim therefor, and means securing said base to said side wall.
8. A box comprising a base, a hollow side wall of inverted channel shape formed from a sheet of material to provide an outer continuous face of predetermined form, a continuous integral upper edge presenting a rim simulating a thick edge, and an inner vertical flange having notches extending from its lower edge substantially to the inner edge of said rim, and means securing said base to said inner flange.
9. A box comprising a base, a hollow side wall of inverted channel shape formed from a sheet of material to provide an outer continuous face of predetermined form, a continuous integral upper edge presenting a rim simulating a thick edge, and an inner vertical flange having notches extending from its lower edge substantially to the inner edge of said rim, lips integral with and extending inwardly from the lower portion of said inner flange, a plurality of tabs partially cut from and integral with said base extending therefrom and engaging said lip and acting therewith to clamp said side wall firmly upon said base.
10. A box comprising a base, covering material on the outer face of the base extending around the periphery thereof and on to the inner face, a hollow side wall of inverted channel shape having an outer flange forming a continuous vertical face, a web forming the upper edge of said wall and presenting a rim simulating a thick wall, and an inner vertical flange, covering material secured to said side wall extending over said outer vertical face, over said rim and along the inner face of the inner flange, and interengaging means upon said base and inner flange clamping said base to said side wall.
11. A box comprising a base, covering material on the outer face of the base extending around the periphery thereof and on to the inner face, a hollow side wall of inverted channel shape having an outer flange forming a continuous vertical face, a web forming the upper edge of said wall and presenting a rim simulating a thick wall, and an inner vertical flange, covering material secured to said side wall extending over said outer vertical face, beneath the lower edge thereof, over said rim and along the inner face of the inner flange, and means securing said base to said side wall with the edges of both covering materials of said base and side wall interposed between the lower edge of the outer flange of the side wall and said base.
12. A box comprising a base, a hollow side wall of inverted channel shape having an outer flange forming a continuous vertical face of predetermined form, a web forming the upper edge of said side wall and presenting a rim simulating a thick wall, an inner vertical flange having at its lower end an inwardly projecting lip, a collar having its lower edge resting upon said lip extending along the upper edge of said side wall and projecting above the same, a plurality of tabs partially cut from and integral with said base and extending therefrom, engaging said lip and acting therewith to clamp said side wall upon said base, and a filler in said box having its peripheral edge frictionally engaging said collar and held in position thereby.
13. A box comprising a base, a hollow side wall of inverted channel shape having an outer flange forming a continuous vertical face of predetermined form, a web forming the upper edge of said side wall and presenting a rim simulating a thick wall, an inner vertical flange having at its lower end an inwardly projecting lip, a plurality of

tabs partially cut from and integral with said base extending therefrom and engaging said lip and acting therewith to clamp said side wall to said base, a cover of like construction hinged to said base, a collar having its lower edge resting upon said lip extending along the edge of said side wall and projecting above the same, a filler in said box having its peripheral edge frictionally engaging said collar and held thereby, and a filler in said cover having its peripheral edge frictionally engaging the side wall thereof and extending over the upper edge of said collar when the cover is closed down upon said box.

15 In testimony whereof, I have signed my name to this specification.

HARRY J. FARRINGTON.
